UNITED STATES PATENT OFFICE

ALBERT MONROE BAY, OF DE SOTO, MISSOURI

ADJUSTABLE DELIVERY BOX

Application filed August 14, 1930. Serial No. 475,259.

This invention appertains to new and useful improvements in receptacles, and more especially to a receptacle of the delivery box type, such as is used by merchants in the delivery of their commodities.

The principal object of this invention is to provide a collapsible delivery box which will require just so much room as the commodities of a particular order will require.

10 During the course of the following specification and claims, other important objects and advantages of the invention, will readily become apparent to the reader.

In the drawings:—

15 Figure 1 represents a bottom plan view of the novel device.

Fig. 2 represents an end elevation of the device.

Fig. 3 represents an end elevation looking 20 at the opposite end from that shown in Fig. 2.

Fig. 4 represents a cross sectional view of the delivery box.

Fig. 5 represents a perspective view of the box in partly extended position.

25 Fig. 6 represents a longitudinal sectional view of the box in partly extended position.

Fig. 7 represents a top plan view of the box in extended position.

Referring to the drawings wherein like 30 numerals designate like parts, it can be seen that the box is divided into a pair of sections generally referred to by numerals 5 and 6. Each of these sections is provided with an end wall 7 and side walls 8—8. Each end

35 wall is provided with a cut-away portion 9 within which a handle 10 is mounted. The upper end portion of the section 5 is provided with a beading 11 telescopic in relation with the outwardly rolled edge portion 12 of the 40 section 6.

As is clearly shown in Fig. 1, a pair of rods 13—13 extend through the clamps 14 on the bottom of the section 6 and enter the elongated guide 15—15 on the bottom side 45 of the section 5. Thus the sections are slidably connected together and to prevent the pulling apart of the sections, the inner end of the section 6 is bent downwardly as at 16, while the inner end of the section 5 is bent 50 upwardly as at 17.

Thus when these sections are fully extended, the end portions 16 and 17 abut to prevent separation of the sections.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

1. A delivery box of the character described comprising a pair of sections, the bottom of one section being provided with elongated guides, and elongated rods each secured at one end to the bottom side of the other section, their remaining ends slidably disposed into the guides on the bottom side of the first-mentioned section. 65

2. A delivery box of the character described comprising a pair of sections, the inner end of one of the sections being provided with a downturned flange, the inner end of the other section being provided with an upturned flange, said flanges being adapted to 70 abut when the sections are fully extended. 75

In testimony whereof I affix my signature.

ALBERT MONROE BAY.
